Paul Arbon.
INVENTOR

BY *Ralph J. Baugh*
ATTORNEY

UNITED STATES PATENT OFFICE.

PAUL ARBON, OF TULSA, OKLAHOMA.

COMBINED CASING HEAD AND SNUFFER.

Application filed June 4, 1924. Serial No. 717,743.

To all whom it may concern:

Be it known that I, PAUL ARBON, a subject of the King of Great Britain, residing at Tulsa, in the county of Tulsa and State 5 of Oklahoma, have invented certain new and useful Improvements in Combined Casing Heads and Snuffers, of which the following is a specification.

This invention relates to provision of 10 means for snuffing or extinguishing fire in oil or gas wells and includes the provision of snuffing chambers in the casing head of novel construction and design.

More specifically the present invention includes an annular casing head of conventional design except for the provision and arrangement of the discharge passages and snuffing chambers and intake and out passages for the latter chambers, whereby such 20 casing head may be utilized by itself or in conjunction with the valved control heads familiar in the art, for extinguishing flames by the use of steam or any desirable chemicals.

25 Numerous features and advantages will more clearly hereinafter appear by reference to the accompanying specification and claims and annexed drawings in which similar characters of reference designate corresponding parts throughout the several views, in which:—

Figure 1 is a side elevation.

Figure 2 is a vertical section.

Figure 3 is a section on line 3—3 of Fig.

35 1, and

Figure 4 is a section on line 4—4 of Fig. 1.

In detail the present invention includes a 40 cylindrical body of suitable material internally threaded at its lower end at 1 for engagement with the exterior threads of the usual casing and provided at its upper end with the annular off-set portion 2 which forms the annular recess 3 for the reception of the cap, valved control head or the like. Fastening means in the form of set screws 4 are provided and suitable packing may be utilized as shown. It will be noted that the lower portion of the body is considerably increased in thickness as at 3' for the obvious purpose of reinforcing the general structure at its point of junction with the casing.

45 A series of radiating internally threaded discharge nipples 5 are located immediately beneath the annular off-set portion 2 and

provide connecting means for the usual discharge pipes which conduct the crude oil from the well. It will be noted that in the present instance these nipples are provided in pairs and the nipples of each pair are located at diametrically opposite points in the periphery of the body. The internal threads are indicated by the reference character 6.

The snuffer is arranged beneath the discharge openings 5 and comprises chambers 7 and 8 in plan of crescent shape. These chambers are formed within the enlarged wall portions immediately above the wall portion 3' which are indicated at 9 and 10. Internally threaded intake ports 12 radiate 50 at intermediate points from said chambers 9 and 10 and it will be noted that the arrangement of these chambers is such that the ports are spaced equi-distant between the discharge ports 5. This arrangement facilitates 55 convenient use and manipulation of necessary tools used in connecting and disconnecting the various pipes.

The snuffer chambers are provided with a common discharge in the form of downwardly directed annular passage 14, the intake end of the passage being located centrally with respect to the snuffer chambers 7 and 8.

From the foregoing it will be obvious to 60 one skilled in the art that the present invention forms an addition to a drilling equipment which may eliminate the use of the control head or which may be used in conjunction with same and in both instances it provides a device not only serviceable and 65 convenient in application and manipulation, but strong and durable and of a design capable of providing the essential extinguishing qualities desired. It will be seen that the 70 present invention is designed to provide a snuffing element to equipment at present involving only a control head and thereby furnish both of the advantages without loss necessarily involved in the use of the 75 combined control head and snuffer. In addition, the present invention facilitates the 80 interchanging of parts and eliminates loss through the destruction of one of the elements where such elements are combined.

85 What I claim as new and useful and desire to secure by Letters Patent, is:—

1. A casing head including an annular body formed with a series of spaced discharge passages, snuffer chambers arranged 90

adjacent to and in advance of said discharge passages and intake and discharge passages for said snuffer chambers.

2. In a casing head including an annular body formed with a series of discharge passages, snuffer chambers adjacent to and in advance of said discharge passages, a common discharge for said snuffer chambers, and a plurality of spaced intake ports for 10 said snuffer chambers.

3. A casing head including a body formed with discharge passages, a snuffer chamber arranged in said head in advance of said passages, a discharge port for said snuffer 15 chamber and intake ports for said snuffer chamber.

4. A casing head formed with a series of discharge ports, a series of snuffer chambers in advance thereof, spaced intake ports for 20 said snuffer chambers and a common discharge port.

5. A casing head formed with discharge passages, a series of snuffer chambers in advance thereof, spaced intake ports for said 25 snuffer chambers and a downwardly directed discharge port for said snuffer chambers.

6. A casing head formed with a lateral discharge passage, oppositely disposed snuffer chambers arranged beneath said dis-

charge passage, intake ports for said snuffer chambers, an annular discharge port communicating with said snuffer chambers, and opening into the bore of said head in advance of said lateral discharge passages.

7. A casing head formed with a series of discharge ports, a pair of arc shaped snuffer chambers formed beneath said discharge ports, intake ports for said snuffer chambers, and intake ports being spaced below and intermediate said discharge ports, and a common 40 downwardly directed discharge port for said snuffer chambers.

8. A casing head formed with enlarged extremities, the upper extremity being provided with an internal annular channel and 45 the lower extremity being internally threaded, discharge ports arranged at diametrically opposite points immediately beneath said upper enlarged portion, arc-shaped snuffer chambers formed beneath said discharge 50 ports, intake ports for said snuffer chambers arranged intermediate said discharge ports, and an annular downwardly directed discharge slot communicating with said snuffer chambers and forming a discharge port 55 therefor.

In testimony whereof I affix my signature.

PAUL ARBON.
